R. McCULLY.
Bottle Stopper and Fastener.

No. 223,526.

Patented Jan. 13, 1880.

UNITED STATES PATENT OFFICE.

ROBERT McCULLY, OF PHILADELPHIA, PENNSYLVANIA.

BOTTLE STOPPER AND FASTENER.

SPECIFICATION forming part of Letters Patent No. 223,526, dated January 13, 1880.

Application filed April 25, 1879.

To all whom it may concern:

Be it known that I, ROBERT McCULLY, of Philadelphia, in the county of Philadelphia and State of Pennsylvania, have invented certain new and useful Improvements in Bottle-Stoppers; and I do hereby declare the following to be a full, clear, and exact description of the invention, such as will enable others skilled in the art to which it pertains to make and use it, reference being had to the accompanying drawings, which form part of this specification, in which—

Figures 1 and 6 are transverse vertical sections of a bottle-neck having my improvements applied thereto. Figs. 2, 3, and 5 are side elevations of the same. Fig. 4 is a perspective of my invention, and Fig. 7 is a detail section of the stopper and valve.

My invention has for its object to provide a stopple adapted to fit the neck of an ordinary mineral-water or similar bottle, and so constructed that pressure of liquids or gas within the bottle will have the effect of tightening said stopple in position.

My invention consists in the peculiar construction of the stopple hereinafter set forth, having reference principally to the provision, in a metallic stopple having an india-rubber gasket and held in place in a bottle by a wire bail, of a central tapering plug having a shank slotted for the passage of said bail, whereby, while the stopple and gasket are held down by the bail, the central plug may be moved upwardly by pressure inside the bottle to compress said gasket vertically and expand it laterally, thereby tightening the joint formed with the bottle-neck.

My invention further consists in the combination, with a swinging stopple and bail, of peculiarly-constructed toggle-links, forming the connection with a collar which encircles the neck of the bottle to which said stopple is applied.

Referring to the accompanying drawings, A indicates a metallic stopper composed of a disk, *a*, with cylindrical neck *a'* and annular flange *a''*. B represents a plug having a tapering end, *b*, and cylindrical shank *b'*, which latter passes through the neck *a'* and projects upwardly into the flange *a''*. Said plug-shank *b'* is slotted laterally at *b''*, and the flange *a''* is notched

or cut away at *a''' a''* for the passage of a wire bail, C. The depending ends *c c* of said bail are turned inwardly to enter openings *d d*, formed in toggle-links D D. Said toggles consist of metallic plates or castings having the lugs *d' d''* and trunnions *d'' d'''*, which latter enter eyes *e e* in a wire collar, E, secured to the neck F of a bottle, or in similar openings *g g* in a semicircular band, G, held on said neck by 55 said collar E. If said band G be employed, it is formed with stops *g' g''*, which limit the movement of the links D D, and prevent the toggles from passing too far from their centers. If the collar E alone be employed, (the collar-band G being omitted,) the links D D will be formed with studs *d'' d'''*, which, when the toggles reach a vertical position, come in contact with said collar E, as shown in Fig. 4, and thereby prevent said toggles passing too far 60 from their centers.

The links D D are bent or deflected at *d''*, so that the lugs *d' d''* stand out from the neck of the bottle, thus preventing contact of the in-turned ends of the bail with said neck, and affording a better purchase for thumb-pressure in fastening and throwing back said links.

H is an india-rubber gasket surrounding the neck *a'* and affording a seat for the conical or tapering portion *b* of the plug B.

The operation is as follows: The parts being connected as shown and described, the stopple, being inserted in the neck of the bottle, is fastened therein by turning down the toggle-links D D until they assume a vertical position, as shown in Figs. 1 and 2. The stopper proper cannot now be drawn out of the bottle-neck until said links are thrown back; but any sufficient fluid or gaseous pressure exerted inside the bottle will force the plug B upwardly or outwardly, compressing the gasket H vertically and expanding it laterally, tightening the joint formed thereby, the slot *b''* in the shank of said plug permitting the movement of the latter, while the stopple proper and bail remain 95 undisturbed.

What I claim as my invention is—

1. The combination, with gasket H and tapering plug B, having shank *b'*, with slot *b''*, of disk *a*, having neck *a'*, with slot *a''*, and bail C, passing through said slots, substantially as described.

2. The combination, with stopple A, having plug B, with slotted shank, the slot thereof being longer than the diameter of the bail-wire, of bail C, passing through said plug, whereby the latter is adapted to be moved upwardly or outwardly to expand the gasket and tighten the joint while said bail and stopple remain stationary, as set forth.
3. The combination, with a stopple, A, and bail C, of toggle D D, constructed and adapted to receive the depending ends of said bail, and a collar, E, or band G and collar E, substantially as shown and set forth.
4. In combination with toggles D D, band G, having stops $g' g'$, to prevent said toggles passing their centers, as set forth.
5. Toggles D, having lugs d' and trunnions d^2 , and deflected at d^3 , substantially as shown and described, and for the purpose set forth.

In testimony that I claim the foregoing I have hereunto set my hand this 23d day of April, 1879.

ROBERT McCULLY.
